UNITED STATES PATENT OFFICE.

FELIX RAMM, OF PITTSFIELD, MAINE.

ADJUSTABLE SHUTTLE CHECK.

Application filed March 28, 1928. Serial No. 265,423.

The present invention relates to improvements in adjustable shuttle checks, and more particularly it relates to an improved means for adjusting the tension upon the binder.

5 It is an object of the invention to provide an improved adjustable tension device that will avoid the expense and nuisance entailed in present constructions.

10 The further object of the invention is to cure present difficulties by an inexpensive and simple form of tension device which will be adaptable to all existing types of shuttle boxes.

15 With the foregoing and other objects in view, the invention will be more fully described hereinafter, and will be more particularly pointed out in the claims appended hereto.

20 In the drawings, wherein like symbols refer to like or corresponding parts throughout the several views,

Figure 1 is a fragmentary perspective view showing a portion of a loom with a shuttle box and the improved tension device.

25 Figure 2 is a top plan view, with parts shown in section, of the binder and improved tension device apart from the shuttle box, and on an enlarged scale.

Figure 3 is a side view of the improved tension lever alone.

30 Referring more particularly to the drawings, a shuttle box of conventional form is shown at 4 as having a number of cells in accordance with the usual practice; and 5 designates the rod by which the shuttle box is customarily shifted.

35 Each cell of the box is provided with a binder. For purposes of illustration, I have shown the binder 6 as pivoted at one end in ears 7 of the shuttle box, the pivot pin being indicated at 8. This pivot pin passes through a cylindrical bearing 9 in the binder. The binder is provided with an intermediate offset portion 10, to which is secured the guide pin 11. A coil spring 12 is wound about the guide pin, engaging at one end against the binder, and its other end against the adjusting lever 13. The pin 11 extends loosely through the lever 13 to admit of the lever 40 rocking freely about its fulcrum as required in the adjustment thereof. The outer end of the guide pin 11 is preferably headed as indicated at 14, although this is not necessary, as the elongated set screw 15, which passes 45 through the opposite end of the lever 13, will

serve to hold the lever up to the coil spring 12. The arm of the lever 13, which engages the coil spring 12, is preferably longer than the arm which carries the set screw. A cylindrical or other bearing 16 in the intermediate portion of the lever is adapted to fit between ears 17 of the shuttle box, which are adjacent the ears 7 and are perforated to receive the pivot pin 18 by which the lever 13 is secured in place outwardly beyond and overlapping the binder 6.

50 The shuttle box 4 is shifted in the usual way, and the shuttles are operated in the customary manner by the picker staff. The shuttle having been driven across the race and into its cell of the shuttle box will encounter the binder, which will check and hold it until the next picker stick operation.

55 By turning the set screw 15, which abuts against the wall of the loom frame or shuttle box, the adjusting lever 13 may be shifted angularly about its fulcrum for the purpose of increasing or decreasing the tension upon the coil spring 12, and consequently, the tension upon the binder. A very delicate adjustment can be had with the set screw 15. This minute adjustment is very important, as it dispenses with the present practice in mills of bending the binder into shape, and re-adjusting and re-bending the binders as the 60 shuttles wear smaller. This bending operation requires considerable time of skilled operatives and results in the final breaking of the binders from the repeated bending operations.

65 Moreover, the improved device will stop the filling "knocking off", which involves a considerable saving in waste. The device will also save the picker on account of the very minute adjustment possible with the 70 set screw; and it will stop "the kinks" due to shuttles bouncing back. The invention will do away with the necessity for hammering the binders, which results in the breakage of shuttles and in many cases the excessive bending of the binders. Then, too, "slamming" 75 with its attendant breakage and the jarring of the timing, the head motion and the bearings, is avoided. In short, the invention will 80 reduce loom breakage and proportionately increase production.

85 It will be obvious that many changes in the construction, combination and arrangement of parts could be made, which could be used without departing from the spirit of my 90

invention, and I do not mean to limit the invention to such details, except as particularly pointed out in the claims.

Having thus described my invention, what I claim and desire to secure by Letters Patent of the United States is:

1. In a shuttle box having a binder, a lever fulcrumed intermediate its ends in the box beyond the binder, a pin carried by the binder for loosely engaging one end of the lever, a coil spring wound about the pin, and engaging both the binder and the lever, and an adjustable set screw carried by the other end of the lever, and taking against the shuttle box for adjusting the spring tension upon the binder.
2. In a shuttle box, a binder pivoted in the box, a lever pivoted close to the pivot point of said binder and extending along the binder to a point remote from the pivot point thereof, resilient means disposed between said binder and the remote end portion of the lever, and means for adjustably moving said lever against the tension of said resilient means toward the binder.
3. In a shuttle box, a binder pivoted in the box, a tension lever also pivoted in the box close to the pivot point of the binder and having arms extending in opposite direction from the lever pivot point, one of said arms extending along the binder to a point remote from the binder pivot point, a pin secured to the

binder near the free end of said arm and extending outwardly from the binder and freely through said arm of the lever, a coil spring wound about said pin between the binder and lever arm, said lever having a second arm extending from the pivot point thereof, and means for acting on said second arm to tend to move the first mentioned arm relatively to the pin toward the binder whereby to compress said spring.

4. In a shuttle box, a binder pivoted in the box, and having an intermediate offset portion, a pin carried by said offset portion and projecting outwardly from the binder, a lever fulcrumed in the shuttle box adjacent the pivotal point of the binder and having a long and a short arm extending oppositely from the fulcrum point, said long arm extending along the binder to a point remote from its pivotal point, the free end of said long arm being offset away from the binder opposite the offset portion of the binder and freely receiving the end portion of said pin, said pin being headed on the outer side of said long arm, a coil spring surrounding said pin and abutting against the long arm and against the offset portion of said binder, and a set screw carried by the short end of said lever and acting against a fixed part of the shuttle box to adjust the angular position of said lever and the tension on said coil spring.

FELIX RAMM.
